UNITED STATES PATENT OFFICE.

WILLIAM ZAVITZ, OF ALGONAC, MICHIGAN.

BAG-HOLDER.

1,292,213.

Specification of Letters Patent. Patented Jan. 21, 1919.

Application filed March 22, 1918. Serial No. 224,014.

To all whom it may concern:

Be it known that I, WILLIAM ZAVITZ, a citizen of the United States, residing at Algonac, in the county of Saint Clair and State 5 of Michigan, have invented certain new and useful Improvements in Bag-Holders, of which the following is a specification.

This invention relates to bag or sack holders for holding sacks in open position 10 while being filled.

The main object of the invention is to provide a simple and efficient device of this character which may be quickly operated to effect the opening or closing thereof and 15 which will be reliably held open until manually released.

Another object is to provide improved means for adjusting the holder vertically for use in connection with sacks of varying 20 lengths.

With the foregoing and other objects in view, which will appear as the description proceeds, the invention resides in the combination and arrangement of parts and in 25 the details of construction hereinafter described and claimed, it being understood that changes in the precise embodiment of the invention herein disclosed may be made within the scope of what is claimed without de- 30 parting from the spirit of the invention.

In the accompanying drawings:—

Figure 1 represents a front elevation of a bag holder constructed in accordance with this invention shown in closed inoperative 35 position,

Fig. 2 is a rear elevation showing the holder in open position, and

Fig. 3 is an edge view thereof.

In the embodiment illustrated a supporting structure is shown in the form of a standard 1 composed of an iron rod having 40 a base in the form of feet 2, any desired number of which may be employed, and which are here shown radiating from a collar 3.

A sleeve 4 is slidably mounted on the standard 1 and is provided with a set screw 5 for holding it in adjusted position. A plate 6 is carried by the sleeve 4 being 50 mounted on the free end of a laterally extending arm 7. This plate 6 is here shown rectangular in form although obviously it may be of any other desired configuration.

A pair of spreading or expanding arms 55 8 and 9 are pivotally mounted on the plate 6 at 10' and 11, respectively, and a link 12

connects these arms, one end thereof being pivoted at 10 to arm 8 while its other end is pivoted at 13 to arm 9 at a point below the pivotal connection of arm 9 with plate 60 6. The arms 8 and 9 are provided at their free ends with lateral extensions 14 and 15 having bag gripping elements 16 at their terminals.

An expanding element in the form of a 65 bar 17 is pivotally connected at 18 to arm 8 and is slidably engaged at its other end with a ratchet rack 21 carried by arm 9, and here shown arcuate in form, the teeth 22 of which are inclined downwardly. The bar 17 70 has a handle 19 at its free end with an opening 20 in which the rack 21 is mounted and which provides for the sliding movement of the bar relatively to the rack, the inner wall of the opening 20 being designed to be lock- 75 ingly engaged with the teeth 22 of the rack to hold said bar in adjusted position as is shown clearly in Fig. 2.

In the use of this bag holder, the parts being in collapsed inoperative position as 80 shown in Fig. 1, a bag, not shown, has the arms 8 and 9 extended into the mouth thereof and then by sliding bar 17 downwardly on rack 21, these arms 8 and 9 are expanded until the elements 16 engage the bag at dia- 85 metrically opposite points. These elements 16 are preferably made arcuate in form and may be of any suitable or desired length so that when the bag is stretched they will hold it open a distance equal to their length to 90 facilitate the insertion of any material de- 95 sired to be placed therein.

When the bar 17 is swung downwardly a sufficient distance to bring the elements 16 into engagement with the bag walls and to stretch said walls to the limit of their open- 95 ing movement, the inner wall of opening 20 will then lockingly engage with one of the ratchet teeth 22 of bar 21 and thus hold the parts in expanded position, a toggle like ef- 100 fect being produced by the connection of the bars 8 and 9 with link 12.

To release the holder, the handle 19 is moved laterally in relation to the holder a sufficient distance to disengage it from the 105 rack bar 21, and said handle may then be moved upwardly to retract arms 8 and 9 and disconnect the elements 16 from the bag.

To adjust the bag engaging members vertically the set screw 5 is released and the 110 sleeve 4 moved up or down on rod 1 until it is positioned at the desired point when

screw 5 is again tightened and the holder is ready for use.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

I claim:

In a bag holder, a support, a member mounted on said support, arms pivoted at

one end to said member in different vertical planes, a link pivotally connected at one end to one arm and at its other end to the other arm, an arcuate rack bar carried by said last-mentioned arm, said arms having lateral extensions at their free ends provided with arcuate bag engaging members, and a bar pivoted to one arm and encompassing and having slidable engagement with said arcuate rack and provided with means for engaging the teeth of said rack to lock said arms in adjusted position.

In testimony whereof I affix my signature in presence of two witnesses.

WILLIAM ZAVITZ.
